FAUCET OR SIMILAR ARTICLE

Henry Dreyfuss, South Pasadena, Calif., assignor to Crane Co., Chicago, Ill., a corporation of Illinois

Application August 8, 1958, Serial No. 52,129

Term of patent 14 years

(Cl. D91—3)

Fig. 1 is a side elevational view of a faucet embodying my new design;

Fig. 2 is a front elevational view thereof; and

Fig. 3 is a top plan view thereof.

The dominant features of my design reside in the portion shown in full lines in the drawings.

I claim:

The ornamental design for a faucet or similar article, substantially as shown and described.
